1 Claim. (Cl. 100—53)

This invention relates to power operated machines, such as presses and the like, and is particularly directed to safety means for such machines capable of stopping the operation thereof and thus prevent damage to the machine.

An object of the present invention is to provide a safety guard or means for presses or like equipment that stops the operation of the machine when an object other than the intended work piece is between the active parts of the machine. The arrangement is such that any body, foreign to the work piece, interposed between the moving parts of the machine, will automatically arrest the movement thereof and necessitate the resetting of the power controls to again initiate the operation of the machine.

This invention contemplates a safety guard means or system for machines having means for moving one work part toward another to act on a work piece disposed between the parts, such machine including manually controlled electrically actuated means for initiating the movement of the movable work part into contact with the work piece, and such guard including an electronic circuit having a portion adapted to be completed through the work parts when a body foreign to the work piece is interposed between the work parts to impress a small electrical voltage across the work parts of the machine to de-energize that portion of the circuit which actuates the machine to instantaneously stop the movement of the movable work part.

Other objects of this invention will appear in the following description and appended claim, reference being had to the accompanying drawings forming a part of this specification wherein like reference characters designate corresponding parts in the several views.

FIG. 1 is a perspective view of a press provided with or embodying the safety guard of the invention.

FIG. 2 is a schematic wiring diagram illustrating the circuits embodied in the invention.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

In the drawings there is illustrated, by way of example, a certain embodiment of the present invention as applied to a pneumatic press of conventional design. The guard consists of a sensitive electronic amplifier controlled by relays in its output circuit in turn connected to the machine with which the guard is used. The guard is actuated by a small electrical voltage impressed across the die or tool used in the machine so that during the down stroke of the ram, should the die come in contact with any foreign object, enough current will be conducted through it to actuate the amplifier to open or close the relays, as the case may require, and instantaneously stop movement of the ram. The machine will remain inoperative until the object causing the stoppage has been removed and a manual reset button on the guard unit returned to the reset position. As a further safety feature, should any external wire leading to the die or to the power source from the guard unit be broken, the machine

2

will be automatically stopped, and will remain inoperative until repairs have been made. For the purpose of operating the guard unit to protect the operator, it is a fact that the human body, or any part thereof, provides an excellent electrical conductor to energize the guard unit to stop the machine.

Referring to FIG. 1 of the drawings, a machine incorporating the present invention has been illustrated. The machine chosen for illustration is a pneumatic or air press having relatively movable work parts for performing an operation on a work piece. The press is inclusive of a base 10 and an upright or standard 12 provided with suitable ways 14. A vertically adjustable head 16 is mounted in the ways 14 and suitably connected to an adjusting screw 17 manipulated by hand wheel 18. By such means the head 16 is raised or lowered to desired position with respect to base 10. Stationary lower die means 20 can be removably secured to base 10 as by means of studs 21. Movable upper die means 23 mounted on a ram 24 cooperate with the lower die to form or otherwise operate on the work piece. Mounted on top of the head 16 is a suitable cylinder 26 within which is provided a piston and piston rod connected to ram 24 to reciprocate the latter in the usual manner. Pressure air is supplied to the top of cylinder 26 through a pipe 28 coupled to a valve 29. Valve 29 is controlled by a solenoid 30 in turn controlled by a foot pedal 32 conveniently positioned with respect to the machine. Foot pedal 32 is electrically connected to solenoid 30 through lead 34, operation of the foot pedal closing a circuit from the source of energy to be later described. The operation of valve 29 results in the operation of ram 24 to force the same downwardly, causing the upper die 23 to cooperate with the lower die 20 to operate on the work piece therebetween. When the pressure is removed from the pedal 32, the circuit is opened, valve 29 returns to normal position and ram 24 and die 23 return to their raised or open position. The machine thus far described may be considered as conventional or standard and is intended only to be illustrative of any suitable mechanism in which are provided relatively movable work engaging members or parts.

As particularly shown in FIG. 2 of the drawings, the safety guard comprises a main electrical circuit operable to control the energization of the valve 29 to actuate the ram 24 of the press and a secondary electrical circuit operable to instantaneously de-energize the main circuit and stop the movement of the ram in the event a short occurs in the secondary circuit prior to engagement of the upper die with the work piece. The invention contemplates the use of the secondary circuit to stop press operation in the event that more than one work piece or an unintended object is interposed between the dies as well as the unintentional placing of the operator's hand or other part of his body between active parts of the machine.

The electrical portion of the invention has been illustrated as being inclusive of a high voltage power supply circuit indicated generally in section A, an isolated bias supply indicated generally in section B, a direct coupled amplifier indicated generally in section C, an interlocked relay circuit indicated generally in section D, and the cooperating movable parts of a machine to be guarded indicated generally in section E. The secondary or safety circuit is directly connected to the bias supply portion of the main circuit.

An alternating current supply having an input 40 which may be the usual 110 volt A.C. supply voltage is connected through a switch 38 to the primary of a transformer T-2. The transformer T-2 has a secondary 42 which supplies plate voltage to a rectifier tube VT-1. Transformer T-2 also has a secondary 44 which supplies

the heater element of tube VT-1, a filter choke CH-1, a variable resistor RE-5 in the amplifier circuit and the relay R-1. Transformer T-2 has a further secondary 46 to supply the filaments of tubes VT-2 and VT-3 of the direct coupled amplifier. The switch 38 also controls the flow of current from the supply 40 to the primary of bias supply transformers T-1 and T-11, the secondaries 47 and 48 of which furnish the grid potential to the input stage VT-2 of the amplifier. The secondaries 47 and 48 also furnish current to the safety circuit 50 reduced to very low potential by resistors RE-3 and RE-4, to energize relay R-3.

The main control circuit for the press or machine receives its energy from the input supply 40 through the switch 38, lead 37, switch 64, lead 34, switch 32 to one side of the load solenoid 30, and from switch 38, lead 36, contacts 57, 58 of relay R-2, contacts 60, 61 of relay R-1, and contacts 62, 63 of relay R-3 to the other side of solenoid 30. Switch 32 is closed to complete the main control circuit and initiate the movement of the ram 24. Switch 64 is closed during normal operation of the device and, upon energization of the guard or auxiliary circuit to stop the operation of the ram, must be opened to deenergize relays R-2 and R-1 to condition the main circuit for normal operation, as hereinafter described.

Relay R-3 is energized from the amplifier circuit after a warm up period as will be understood. Then upon closing of the manually actuated press energizing switch 32 which may be foot or hand operated, current is supplied to the load circuit and the press to energize solenoid 30 to actuate valve 29. Assuming that the proper work piece is between the active parts of the machine, and that no foreign object such as the operator's hand is between these parts, the ram 24 will be operated to perform its intended function. However, in the event an improper work piece or the operator's hand is between movable parts of the machine, the ram will descend until contact is made with such object, at which time the safety circuit is energized to cause current to flow from the active parts of the machine to the ground 22, causing a reversal of current in the amplifier circuit, energizing relays R-1 and R-2, and de-energizing the solenoid 30 to close valve 29 and stop descent of the ram 24.

To accomplish normal press operations, the instrumentalities associated with the ram of the press are shown in section E of the diagram. Here it will be noted that a double lead 51 is connected to the movable die 23a, each lead in turn being connected to one side of a single pole switch 52 and 53 respectively. Switches 52 and 53 are in turn connected by suitable leads to the safety circuit 50, the switches being provided with actuating arms 52a, 53a, respectively. These switches 52 and 53 are actuated by means such as cam 24a on ram 24, the distance between cam 24a and arms 52a, 53a being adjustable in relation to the position of die 23a with respect to 20 so that switches 52 and 53 are opened by cam 24a pushing downwardly on arms 52a, 53a to disconnect the safety circuit during the time the die 23a is in actual contact with the proper work piece. In other words, the switches are positioned with respect to cam 24a so that the guard is effective until the space between the dies would no longer permit the entrance of any object foreign to the proper work piece. To reset the guard circuit automatically when switches 52 and 53 have been opened during normal operation to operate on a work piece, a switch 55, in series with reset switch 64, is also actuated by movement of the die member 23a and can be set to be opened during the upstroke of the ram or if desired at the start of the down stroke. Opening of switch 55 which is connected to coil of relay R-2 de-energizes the relay R-2 and thus R-1, of the interlocked relay circuit.

In order to operate a machine with which the guard has been incorporated, current for the machine must first pass from contact 57 to contact 58 of relay R-2. From

contact 58 current is supplied to contacts 59 and 60 of relay R-1, which closes the circuit to contact 61. From contact 61 the current passes to contact 62 of relay R-3, which closes the circuit to contact 63 thereof, completing the circuit to the load solenoid of the machine. These relays, R-2, R-1, and R-3, control only the hot side of the main power line while the return side of the line is connected through a single point push switch 64, used to reset the guard, and then to the manual switch 32, in turn connected to the other side of the load solenoid 30. To maintain this condition for normal operation of the machine with which the guard is used, it is to be understood that the coils of relays R-1 and R-2 must not be energized while the coil of relay R-3 is normally energized.

The coil of relay R-1 is connected in series with the plate circuit 66 of the direct coupled amplifier in section C of the drawings. This amplifier is normally operated in an "off" condition, the grids of both tubes being biased strongly negative in relation to the cathodes, thus preventing the flow of current through the tubes. Both grids of the tube VT-2 are connected to the positive side of separate isolated D.C. power supplies as shown in section B. The negative sides of both D.C. supplies are connected through circuits 50 and 51 to an insulated portion of the dies in the controlled machine as above described. It is to be further noted that both grids of tube VT-2 are grounded through resistors RE-1 and RE-2 having capacities in the range of 100,000 ohms to 12 megohms, it being understood that the greater the resistance of RE-1 and RE-2, the more sensitive the guard becomes.

If contact is made between die parts 20 and 23a of the machine by even the slightest touch of the operator's finger, current will flow through the finger from 23a to 20, and to ground 22 and thence from ground to the grid resistors RE-1 and RE-2 and returned to the positive side of the bias supply. Such current flow will cause a voltage drop across resistors RE-1 and RE-2 to produce a positive charge on both grids of tube VT-2, causing this tube to draw current. Current for tube VT-2 is drawn through RE-3, and is adjusted so the drop in RE-3 will cause a positive charge to appear on the grid of tube VT-3, bringing it to equal potential with the cathode, thus causing this tube to draw between 30 and 40 milliamperes of plate current, which is more than sufficient to insure operation of relay R-1 in series with the plate circuit of VT-3.

When the tube VT-3 draws current, it will energize the coil of relay R-1, breaking the contacts between contacts 59, 60, and 61 thereof, instantly shutting off flow of current to the controlled machine or load. Contacts 59 and 60 now being connected to contacts 68 and 69 will cause relay R-2 to be energized bridging contacts 57 and 70 and become self holding. Current to the machine or load will be permanently shut off by relay R-2 until reset switch 64 is opened to allow relay R-2 to de-energize. It is to be understood that once relay R-1 becomes energized, even if for only a split second, relay R-2 will be activated and regardless of the fact that should relay R-1 return to normal, no current can be fed to the machine or load because relay R-2 remains self holding until reset.

Relay R-3 is normally energized by current from the grid bias supply from which two leads are connected to the die 23a in addition to controlling the separate grids of tube VT-2, to form a complete circuit for the coil of relay R-3. In the event one or both of these wires becomes broken relay R-3 will de-energize, breaking contact between contacts 1 and 6 thereof, and current to the machine or load will be interrupted. As a further precaution, the breaking of either of these wires causes the signal voltage to be fed to the grid circuit of tube VT-2 at the instant of breaking, causing relay R-1 to be momentarily energized. Relay R-2 will become self holding and the circuit will be broken not only to the

relay R-3 but also to relay R-2. The pressing of the reset switch 64 under these conditions will not restore current to the machine until the broken wire has been repaired so that relay R-3 can again be energized.

What is claimed is:

In a press having a work support and a ram movable toward and away from the work support, die means interposed between the work support and the ram, power means for effecting movement of said ram toward the work support to actuate said die means to perform an operation on a work piece, a main electrical circuit, control means for said power means including switch means for closing and maintaining said main electrical circuit energized during normal press operation, means including a normally open secondary electrical circuit completed only by an object foreign to the normal work

piece to de-energize the main electrical circuit for stopping the movement of the ram and rendering said control means ineffective, and means including manually operable reset switch means to de-energize said secondary circuit so that said main electrical circuit can be energized by said control means, said secondary circuit including switch means actuated upon predetermined movement of the ram to maintain said secondary circuit open during normal operation.
